UNITED STATES PATENT OFFICE.

SWAN SMITH, OF WHITE BEAR, MINNESOTA.

CREASING MACHINE.

Application filed March 15, 1920. Serial No. 366,105.

To all whom it may concern:

Be it known that I, SWAN SMITH, a citizen of the United States, residing at White Bear, in the county of Ramsey and State of Minnesota, have invented a new and useful Creasing Machine, of which the following is a specification.

My invention relates to improvements in creasing machines.

10 Its object is to provide a machine of this kind, supplied with coacting dies carried upon adjacent rotors and adapted to be quickly, easily, and accurately adjusted upon said rotors.

15 A further object is to provide coacting male and female dies particularly, though not exclusively, for creasing paper, the female dies having readily expansible and contractible members to suit different dies or different members of reversible male dies.

20 A further object is to provide a female die for creasing paper, said die being supplied with a self adjusting seat adapted to avoid the shearing effect, which would otherwise result as the male die registers with the female die, and eject the creased paper from the female die, as the male die is withdrawn therefrom.

25 A further object is to provide coacting male and female dies for creasing paper, the former presenting a concave bearing surface to the paper, whereby the pressure of the male die against the paper is exerted along the inner lines of fold within the crease, thus avoiding compressing the paper throughout the base of the channel and at the same time forming well defined lines upon which the sides of the channel are turned.

30 A further object is to provide in a device of this kind, an indicator adapted to turn with a rotor and a stationary graduated scale in juxtaposition to said indicator to aid in procuring desired adjustments of the dies upon said rotors.

35 In the drawings, Fig. 1 is a side elevation of a machine embodying my invention; Fig. 2 is an end elevation thereof; Fig. 3 is an elevation in detail illustrating a portion of one of the female dies, a section thereof being broken away to show parts otherwise concealed; Fig. 4 is a sectional view taken on the line 4—4 of Fig. 3; Fig. 5 is a similar view taken on the line 5—5 of Fig. 3; Fig. 55 6 is a sectional view in detail taken on the line 6—6 of Fig. 1 and illustrates particu-

larly one of the stops for securing the dies in registration; Fig. 7 is a detail view illustrating the arm for withdrawing said stop and Fig. 8 is a detail sectional view showing a clamp for adjustably securing the end of a die holder upon its supporting wheel.

60 In the drawings, I have used the reference numeral 10 to indicate a frame. Shafts 11 journaled, one above the other, in said frame are connected through gears 12 thereon. Power for turning these shafts may be applied to either shaft in any suitable manner. Aligned supporting wheels 13 having rims 14 of considerable width are secured to 65 said shafts 11. Die holders comprising holder bars 15 T shaped in cross section and supplied with bevelled lugs 16 at the opposite ends thereof, are adjustably secured in axial relation upon the rims 14 of the supporting wheels 13. In Fig. 8; I have illustrated a clamp 17 which I prefer to employ in adjustably, securing said holders upon the supporting wheels. These clamps 17 have 70 pivotal bearings at one end thereof in depressions 18 in the holder bars 15, the free ends of said clamps overlapping the margins of adjacent rims 14 and removably held thereagainst by means of bolts 19 passing through bores 20 in said clamps and fitted in 75 threaded bores 21 in said holder bars. Female dies A are carried by one set of holder bars 15, each including laterally expansible and contractible members or bars 22 having threaded bores 23 therein. Stub shafts 24 80 revoluble in a holder bar 15 are supplied with oppositely threaded portions 25, which are fitted in the threaded bores 23 of said die members 22 and carry said members. Each stub shaft 24 carries a spur gear 26 85

which meshes with a rack-bar 27, slidably mounted upon bolts 28, threaded in a holder bar 15. A shifting gear 29 journaled on one of the die members 22 is formed with a key receiving projection 30 and is designed to 90 shift the adjacent rack-bar longitudinally, thereby turning the stub shafts 24 and opening or closing the die members 22. Interposed between said die members 22 of each female die is a yielding bar or seat 31. 95 Guides 32 attached to said seat slide in bores 33 in the holder bar 15 and coiled springs 34, also in said bores 33 and abutting against said guides, operate to yieldingly depress the seat or bar 31. Pins 35, anchored 100 in the holder bar and passing through ways 36 in the sides of said guides, limit the out-

ward movement of said bar through the action of said springs 34.

Male dies B are carried by one set of holder bars 15. These bars are formed with 5 longitudinal grooves 37 therein to receive said male dies. In my preferred structure, I employ reversible male dies, each comprising a creasing bar, one side thereof being reduced in thickness as compared with the 10 other side. These creasing bars are reversible edgewise within the grooves 37 in the holder bars and are secured in selected positions within said grooves by means of set screws 38 threaded in the holder bars. The 15 narrow sides or bearing surfaces 39 of the male dies are concave. By this arrangement, the maximum pressure is applied to paper stock along the inner lines of fold at the base of the creases or channels formed 20 between the male and female dies. This is advantageous for the reason that the lines of fold are definitely scored without distorting the stock in the base of the crease or channel.

25 In adjusting companion dies upon the supporting wheels 13, said wheels are first turned to positions, wherein said dies rest in registration. Similar stops 40 are furnished to secure said dies in such registering positions and thus hold the same after 30 the clamps 17 are temporarily loosened and while the supporting wheels 13 are turned to secure a different relation between said wheels and dies. Said stops 40 are placed 35 upon opposite sides of the frame, each having a beveled socket 41 therein to receive the beveled lugs 16 on the ends of adjacent holder bars 15. Each stop 40 slides horizontally in a guide 42 on the frame 10. An 40 annular shoulder 43 on a stop 40 fits in a bore 44 in the frame 10 and a coiled spring 45 in said bore bears against said shoulder and operates to yieldingly hold said stop in 45 extended position in engagement with the lugs 16 on the holder bars 15. A rod 46 attached to the stop 40 slides in the frame 10 and on the outer end thereof is a collar 47 having an inner cam surface 48. An arm 49 slidable in a guide 50 on the frame, is 50 furnished with a handle 51 for shifting the same and is formed with depressions 52 and 53 therein, in which a latch spring 54 engages to yieldingly secure said arm against displacement. The end of said arm 55 opposite said handle is bifurcated to receive the rod 46 and is formed with a wedge-shaped cam surface 55 to engage the cam surface 48 on said collar 47. In one position of the arm 49, the coiled spring 45 is 60 free to hold the stop 40 in engagement with the lugs 16 on the holder bars 15. In shifting said arm forward from this position, the cam surface 55 on the arm engages the cam surface 48 on the collar 47, thus withdrawing the stop 40 from the lugs 16,

against the action of the coiled spring 45. Continued movement of the arm 49 to position wherein the latch spring 54 registers with the depression 53 in said arm shifts the collar 47 upon a shoulder 56 on said arm 70 and results in securing the stop 40 in inoperative position. Reverse movement of the arm again permits the functioning of the coiled spring 45.

To provide for readily and accurately adjusting the dies, I have supplied an indicator 75 57 and a graduated scale 58, the former being removably applied to one of the shafts 11, while the latter is fixed upon the frame 10. With reference to this indicator and 80 scale, desired adjustments of the dies may be quickly and easily accomplished.

Among other advantages residing in my improved device, it will be noted that the yielding seat 31 in each female die minimizes the shearing effect of the coacting 85 male die and, further, that said seat operates to effectually eject the creased stock from said female die.

Changes in the specific form of my invention, as herein disclosed, may be made within 90 the scope of what is claimed without departing from the spirit of my invention.

Having described my invention what I claim as new and desire to protect by Letters Patent is:

1. In a device of the class described, coacting male and female dies, the former comprising a reversible bar embodying creasing elements of different widths and thicknesses and the latter including laterally expansible and contractible members capable of adjustment to suit the different creasing elements of the male die, and a yielding seat between said expansible and contractible members designed to adapt itself to the various widths of the different creasing elements.

2. In a device of the class described, coacting male and female dies, the former comprising a reversible bar embodying creasing elements of different widths and thicknesses and the latter including laterally expansible and contractible members capable of adjustment to suit the different creasing elements of the male die, and a yielding seat between said expansible and contractible members designed to adapt itself to the various widths of the different creasing elements and also serve as a stripper for the 115 female die.

3. In a device of the class described, a frame, companion rotors revoluble in said frame, coacting dies carried laterally on said rotors and capable of adjustment thereon 125 and a stop on said frame designed to secure said dies in intermeshing relation and thus hold the same while the rotors are turned with respect thereto.

4. In a device of the class described, a 130

- frame, companion rotors revoluble in said frame and geared one with the other, die holders carried laterally upon said rotors, means for adjustably securing said holders upon the rotors, coacting die members carried upon said holders, stops on the sides of the frame adapted to engage the opposite ends of said holders when the die members thereon are intermeshed and means for actuating 10 said stops.
5. In a device of the class described, die holders, a male die carried in one of said holders, a female die on the other holder including side members with threaded bores 15 therein and supporting shafts for said members journaled in said holder and having opposed threaded portions fitted in the threaded bores in said side members, said supporting shafts being turned in unison, 20 to open and close said side members, by means including spur gears on said shafts and a slidable rack-bar meshing with said spur gears, and a yielding seat interposed between the side members of the female die.
25. 6. In a device of the class described, die holders, a male die carried in one of said holders, a female die on the other holder comprising side members with threaded bores therein and supporting shafts for said 30 members journaled in said holder and having opposed threaded portions fitted in the threaded bores on said side members, said supporting shafts being designed to be turned in unison, to open and close said side 35 members by means including spur gears on said supporting shafts, a rack-bar meshing with said spur gears and a shifting gear meshing with said rack.
7. In a device of the class described, rotors 40 adapted to turn in unison, female dies adjustably mounted upon one of said rotors, male dies adjustably mounted upon the other rotor, each being adapted to coact with a female die on said first mentioned rotor and 45 means adapted to hold the dies when intermeshed and secure the same as the rotors are turned with respect thereto.
8. In a device of the class described, a pair 50 of rotors gearing connecting said rotors, female dies adjustably mounted upon one of said rotors, male dies adjustably mounted upon the other rotor, each being adapted to coact with a female die on said first mentioned rotor, means adapted to hold the dies 55 when intermeshed and secure the same in such relation as the rotors are turned with respect thereto, an indicator adapted to turn with one of said rotors and a fixed graduated scale, adjacent said indicator, by which adjustment of the rotors with respect to the 60 dies thereon may be readily and accurately determined.
9. In a device of the class described, coacting male and female dies, the latter including laterally expansible and contractible 65 members capable of adjustment to suit male dies of different thickness and a yielding seat between said expansible and contractible members.
10. In a device of the class described, coacting male and female dies, the former comprising a reversible bar embodying creasing elements of different thickness and the latter including laterally expansible and contractible members capable of adjustment 70 to suit the different creasing elements of the male die.
11. In a device of the class described, a frame, a pair of revoluble supports in said frame, longitudinally arranged die holders, 75 adjustably mounted upon said supports, each holder being supplied at the ends thereof with lugs, die members carried by said holders, opposed stops in said frame 80 slid- axially with respect to said revoluble supports and adapted to engage the lugs at both ends of companion holders, when the die members thereon are in mesh, means for yieldingly holding said stops in engagement 85 with said lugs and means for withdrawing 90 the stops from the lugs.
12. In a device of the class described, a pair of rotors cooperating dies carried upon said rotors and capable of adjustment thereon and means to maintain the relative positions of the dies as the rotors are turned 95 to secure different adjustments of said dies with respect thereto.
13. In a device of the class described, coacting male and female dies, the latter including a yielding seat and co-operating crease forming members fixed with respect to the yielding seat, said male die being designed to pass between said crease forming 100 members and present a concave surface to 105 said seat.
14. In a device of the class described, a reversible male die and a female die, the former presenting concave bearing surfaces to the seat of the latter.
15. In a device of the class described, coacting male and female dies, the latter having a yielding seat for the bearing surface of the former and including co-operating crease forming members fixed with respect 110 to said yielding seat.
- In testimony whereof, I have signed my name to this specification.

SWAN SMITH.
